PULPWOOD SAW FRAME

William Hastings Graff, Philadelphia, Pa., assignor to Henry Disston & Sons, Philadelphia, Pa., a corporation of Pennsylvania

Application April 14, 1943, Serial No. 483,011

7 Claims. (Cl. 145—33)

1

This invention relates to improvements in saw frames and more particularly in frames for pulpwood saws.

A principal object of the invention is to provide a simple and durable device for facilitating insertion and subsequent tensioning of the saw blade in the frame, and for releasably retaining the tensioned blade in the frame.

To this end, the invention contemplates provision in the frame, as a permanent part of the latter, of a novel and improved form of blade-retaining and tensioning device.

Another object of the invention is to provide a blade-retaining and tensioning device of the stated character which shall be substantially tamper-proof.

In the attached drawings,

Fig. 1 is a side view of a frame made in accordance with my invention;

Figs. 2, 3, 4 and 5 are, respectively, views in perspective of elements of the blade-tensioning and retaining device;

Fig. 6 is a view illustrating a preferred method of manufacturing the handle element illustrated in Fig. 2;

Fig. 7 is an enlarged sectional view on the line 7—7, Fig. 1;

Fig. 8 is an enlarged sectional view on the line 8—8, Fig. 1, and

Fig. 9 is a fragmentary elevational view from the inside of the frame of the extremity of the frame appearing at the right in Fig. 1.

With reference to the drawings, the body of the frame, designated by the reference numeral 1, may be made of steel tubing and may have the typical U-shape, as illustrated in Fig. 1. At one end, the frame is formed with a suitable socket designated generally by the reference numeral 2 for reception of one end of the saw blade. In the present instance, the blade is provided at the ends with transversally projecting pins 3, and the pins at the one end are received in slots 4 in the end of the frame which constitute elements of the said socket. The end of the frame is slotted longitudinally on the inside for reception of the blade, as shown in Fig. 8 at 5, and the metal of the frame at each side of the slot 5 is flattened so that the slots 4—4 are formed in part in the flat contiguous walls 6 of the slot, and in part in the rounded portion 7. This permits the blade to be slid inwardly into the slot 5 with the pins in the relatively wide rounded portion 7 and also permits the pins to enter the slots 4—4 through the more widely separated inner ends thereof which lie in the said rounded portions of the

2

frame. The construction provides a simple and positive means for retaining the one end of the saw blade and avoids the necessity for non-integral blade-retaining means at that end of the frame.

Pivottally secured at the opposite end of the frame is a blade-tensioning and retaining device designated generally by the reference numeral 11. This device consists of the elements illustrated in Figs. 2 to 5 inclusive, there being a single handle element, shown in Fig. 2, and two each of the elements shown in Figs. 3, 4 and 5.

As best shown in Fig. 7, this end of the frame 1 is flattened and bifurcated so as to provide a passage between the branches of bifurcation for the saw blade. To the outer face of each of the flat branches 12 and 13 is secured, preferably by welding, one of the washers 14 shown in Fig. 5. As illustrated, each of these washers is apertured at 15 for reception of a pintle pin 16, see Fig. 4, and one end of the aperture 15, namely that end which adjoins the surface of the associated branch 12 or 13, is countersunk, as illustrated at 17, for reception of a correspondingly formed flange 18 of the pin 16. The pin is inserted in the washer before the latter is secured to the frame so that the flange 18 is confined between the washer and the associated branch of the frame, and pins are thereby secured in the frame for a purpose hereinafter described. With reference to Fig. 7, it is to be noted that the inner end of each of the pins is provided with a cylindrical projection 19 which enters an aperture in the associated frame branch, this constituting a means for locating the pins 16 in axially aligned positions in the frame. To this end, the apertures 21 are formed in accurate alignment with each other.

Each of the pins 16 is adapted to receive one of the blade retaining elements 22, illustrated in Fig. 3, of which one is right handed and the other left handed, see Fig. 7. Each of the elements 22 is provided with an aperture 23 countersunk on the outer face of the element as illustrated at 24. After the elements are inserted on the pins in relative positions illustrated in Fig. 7, the ends of the pins are riveted over into the countersinks 24 so as to secure the elements 22 on and preferably to the pins. After application of the elements 22 to the pins in this manner, the handle element 25, shown in Fig. 2, is placed in position with the terminal branches 26—26, against the outer faces of the respective elements 22 and overlying the outer riveted ends of the pins 16, and are secured, preferably by welding,

in this position to the said elements; or the relative positions of the handle element 25 and blade-retaining element 22 are best shown in Figs. 1 and 7, it being noted that the handle extends substantially at right angles to the longitudinal center lines of the elements 22.

Each of the elements 22 comprises an inset end portion 27 and in each of these end portions is a slotted recess 28. The recesses 28 are adapted to receive the pins 3 at the end of the saw blade whereby when the handle 25 occupies the position shown in Fig. 1, in which it bears against the outer side of the end of the frame, the saw blade is locked in tensioned position within the frame. It is to be noted that the handle 25 may be readily produced from sheet metal from a flat blank of the general form illustrated in Fig. 6; and that each of the elements 14 and 22 are similarly adapted to be produced from sheet metal.

With the two elements 22 secured respectively to the branches 26 of the handle element 25, these three elements form in effect an integral bell crank lever which is bifurcated as to the one arm which comprises the elements 22 and as to the adjoining portion of the other arm consisting of the handle element. The branches of this bifurcated lever are pivotally secured, respectively, to the branches 12 and 13 of the bifurcated end of the frame. This preserves a passage for the saw blade between the several branches and is productive of an entirely symmetrical structure in which the strains are nicely balanced between the pivot pins 16.

It is to be noted also that by securing the pivot pin 16 to the elements 22, as previously described, the said pins will rotate with the aforesaid bell crank lever and with respect to the branches 12 and 13 of the frame and the washers 14 which are secured to said branches. The pins thereby find a bearing not only in the washers 14 but also in the said branches 12 and 13 by reason of the projection 19 of the pins which occupy the apertures 21 of the branches. This extended bearing makes for strength and durability.

In inserting a saw blade in the frame, the handle element 25 is drawn away from the frame, as indicated in broken lines in Fig. 1, and through an angle of approximately 180° or until the retaining elements 22 are brought to the inside of the frame. The pins 3 at one end of the saw blade are then inserted in the socket 2 and the pins at the opposite end in the now inverted recesses 28. The handle element 25 is then turned to the operative position shown in full lines in Fig. 1, the blade being thereby placed under strong tension in the resilient metal frame. In this latter movement, the blade is carried between the frame branches 12 and 13, and in order to facilitate entrance of the blade the inner edges of the said branches are beveled, as indicated at 29 in Fig. 9, these bevels acting as guides and precluding snagging of the blade on either side of the slot entrance. When the arms 22 are in the operative position shown in Fig. 1, the line intersecting the pins 3 at the opposite ends of the blade is above the axis of the pivot pins 16 so that the tension operates to retain the blade-tensioning and retaining device in the operative position. The blade may be released from the frame by a simple reversal of the steps previously described.

It is to be noted that in this device, the working elements of the blade-tensioning and retaining device, are, in effect, housed within the hollow interior of the bifurcated end of the handle 25

and are therefore concealed and not accessible for tampering. The parts being welded as described, the entire device becomes in effect a permanent part of the frame but so that there

is no possibility of any of the elements of the device becoming loose from the frame and being lost or mislaid. The device, while simple in form, is highly durable, and the encasement of the working elements of the device within the hollow handle, as described above, precludes damage to these parts in the rough handling to which saws of this type are frequently subjected.

I claim:

1. A saw frame of the type set forth, said frame having flat relatively spaced portions at one end defining the sides of a narrow slot extending longitudinally from the extremity of the frame in the plane of the latter, a washer secured to the outer face of each of said flats, a pin having a

20 head portion confined between each of said washers and the associated flat portion of the frame and projecting outwardly through an aperture in the washer, said pins being aligned and defining a pivotal axis at right angles to the plane of the slot, a bifurcated lever having its branches over-

25 lying the outer ends of the pins, a washer secured to the outer end of each of said pins and secured respectively to the inner faces of said lever branches whereby the said lever is attached to 30 the pins, blade-retaining means in the said lever branches eccentrically positioned with respect to said pivotal axis, and means for adjusting the lever about said axis.

2. A saw frame of the type set forth, said frame 35 having flat relatively spaced portions at one end defining the sides of a narrow slot extending longitudinally from the extremity of the frame in the plane of the latter, aligned pins projecting respectively from the outer faces of said flats

40 and defining a pivotal axis at right angles to the plane of the slot, a bifurcated lever having its branches overlying the outer ends of said pins, means on the inner faces of said branches for attaching the lever to the pins, blade-retaining

45 means in the said branches eccentrically positioned with respect to said pivotal axis and means for adjusting the lever on the frame about said axis.

3. A saw frame of the type set forth, said frame 50 having flat relatively spaced portions at one end defining the sides of a narrow slot extending longitudinally from the extremity of the frame in the plane of the latter, a pair of pins projecting respectively from the outer faces of said flats and

55 having their inner ends inserted in aligned apertures in said flats, a washer having an aperture for passage of said pin and secured to the outer face of each of said flats, each of said pins having a head portion confined between a washer and

60 the outer face of the associated flat, a pair of arms permanently attached to the outer ends of the pins respectively, and a bifurcated arm having its branches overlying and secured against the outer faces of the said arms and forming with

65 the latter a bell crank lever adjustable on the frame about the common axis of said pins, and blade-retaining means in the first named arms eccentrically positioned with respect to said pivotal axis.

70 4. A saw frame of the type set forth, said frame having flat relatively spaced portions at one end defining the sides of a narrow slot extending longitudinally from the extremity of the frame in the plane of the latter, a pin projecting from

75 the outer face of each of said flats and having

its inner end rotatably inserted in an aperture in the associated flat, said apertures being aligned and said pins defining a common pivotal axis at right angles to the slot, a washer secured to the outer face of each of said flats and having an aperture therein for passage of the pin, said pins having head portions loosely confined between the associated washer and the frame, a bifurcated lever having its branches rigidly secured respectively to the outer ends of the pins, blade-retaining means in said branches eccentrically positioned with respect to said pivotal axis, and means for adjusting the lever about said axis.

5. A metal saw frame having a flat bifurcated end portion, said bifurcations having aligned apertures, a pintle pin having a cylindrical end portion journaled in each of said apertures and having also an adjoining collar engaging the outer face of the bifurcation, a washer secured to the said outer face of each of the bifurcations and having a journal aperture for reception of the pin and a countersunk recess at one end of said aperture for reception of the said collar, said pins being thereby rotatably secured in axially aligned relation in the said bifurcations, and blade-retaining means pivotally mounted on the outwardly projecting ends of said pins.

6. A saw frame having a bifurcated end portion, a blade-retaining member having bifurcations adjacent to the bifurcations of the frame, and aligned pintle pins entirely confined by and between the said bifurcations and permanently pivotally connecting the bifurcations of the retaining member with the bifurcations of the frame respectively.

7. A tubular metal saw frame of generally U-shape, the wall at one end of the frame being slit at the inside and being unbroken at the outside of the U and being in part flattened in an area immediately adjoining said slit so as to provide a flat sided blade-receiving slot entering from the inside of the U and terminating in an unbroken tubular portion, and an elongated slot in each side of the wall for reception of blade-retaining elements, each of the slots lying in part within the said tubular and in part within the adjoining flat portion of the wall.
